THREAD CLEANER

Emil W. Young, Brooklyn, N. Y.

Application July 21, 1932, Serial No. 623,767

5 Claims. (Cl. 28—70)

The invention relates to thread cleaners, such as are used on textile machines of various types, for removing and detecting fluff, lint, slubs, knots, foreign matter, enlargement or other imperfections from or on threads or other filaments.

It has for one of its main objects to provide a device on which the blades between which the cleaning is performed may be readily and speedily removed and inserted without the use of any tools, or the adjustment of any screws or other adjusting means. Another object is to so mount the cleaning blades that while sideward movements may take place, due to the movement of the thread passing between the blades, the blades are positively restrained from any movement in a direction from or toward which the thread travels.

A further object is to so construct the blades that they cannot be adjusted or tampered with by the operator. A still further object is to provide means to prevent the blades from being inadvertently inserted in a wrong position. Further objects are to provide a thread cleaner of simple, accurate and strong construction, which can be attached to any machine where such a device is needed, and which can be manufactured at a low cost.

These and various other objects and advantages will be readily understood from the following description and from the accompanying drawing of preferred embodiments of the invention in which, however, modifications may be made without departing from the scope of the appended claims. In the drawing

Fig. 1 is a side elevation of one embodiment of the improved thread cleaner,

Fig. 2 a front elevation of same,

Fig. 3 a plan view,

Fig. 4 a plan view of one of the blades used in the device illustrated in Figs. 1, 2 and 3,

Fig. 5 a plan view of a modification of the device,

Fig. 6 a fragmental and enlarged sectional side view of some of the parts shown in Fig. 5,

Fig. 7 another modification, and

Fig. 8 a fragmental and enlarged side view of some of the parts shown in Fig. 7.

Referring first to Figs. 1 to 4 inclusive, the device comprises a bracket 10 which is provided with threaded holes 11 and 12 at its upper and lower ends, a forwardly extending support 13, and a rearwardly extending clamping member 14. While this bracket lends itself readily to attachment on many types of textile machines, it is illustrated merely as a type of bracket and it will be understood that brackets of other construction

may be employed. The holes 11 and 12 make it possible to attach thread guides, such for example as shown at 15 and 16, either at the top or bottom of the bracket, or at both the top and bottom, as may be found most suitable for the work to be performed.

A channel-shaped socket 17, having overlapping flanges 18 and an upwardly extending bearing 19, is pivoted on the support 13 by means of a bolt 20 and nut 21. The blades 22, between which the thread to be cleaned passes and which are spaced at various distances to operate on threads of various gauges, are secured on the front end of a plate 23 by rivets 24. The plate is bifurcated at its front end 25 to allow the free passage of the thread through the slot formed between the blades. It also has a notch 26 punched at its rear end 27 so as to straddle the bearing 19 when the end is inserted in the socket 17.

A wire spring 28 is wound around the bearing 19 and formed in the shape plainly shown in Fig. 3. The downwardly-bent, free ends of the spring engage in angular notches 29 and 30 cut respectively in the socket 17 and in the plate 23. This construction makes it possible to lock the blades securely in the socket and still enable them to be withdrawn by a light forward pull. While the blades and the socket are free to turn sidewardly on the bolt 20 to accommodate the motion of the thread passing between the blades, the overlapping flanges 18 effectively prevent any movement of the blades and holder in a direction either from or toward which the thread is traveling.

To prevent the blades from being inserted upside down in the socket, a small upwardly projecting stop 31 is formed on the rear end of the blade 23. This stop will pass between the flanges 18 but will encounter the bottom part of the socket should the blade be turned the wrong way.

In the modification shown in Figs. 5 and 6, a flat spring 32 has been substituted for the wire spring 28. This flat spring, which engages under the flanges 18 and which has a hole 33 through which the bearing 19 passes, is provided with a transverse ridge 34 which co-acts with a groove 35 milled transversely in the plate 23.

In the modification shown in Figs. 7 and 8, no separate spring is employed but the socket 17 is made of spring metal and the overlapping flanges 18 are formed in such a manner as to form springs 36 which terminate in curved ridges 37 at their free ends. These ridges engage in grooves 38 milled in the plate 23.

From the foregoing it will be seen that the present invention makes it a simple matter to

exchange the blades in the socket and that, as the blades are permanently riveted together in sets, there is no danger of the adjustment of the spacing of the blades being tampered with or 5 accidentally getting out of adjustment. By riveting the blades on a separate plate, as here shown, instead of merely milling or sawing the slot 39 in the blades, it is possible to grind the sides of the slot and thus assure greater accuracy and less 10 wear on the thread. By locating the spring means between the socket and the support 13, as shown in Fig. 1, there is no danger of their being clogged with floss or dirt.

Having described my invention and its advantages, what I claim as new and wish to protect by Letters Patent is:

1. A thread cleaner of the class described comprising, a bracket having means for attaching it to the machine on which it is to be employed and 20 means for attaching one or more thread guides, a support formed on said bracket, a socket pivoted on said support, a plate having a pair of thread-cleaning plates secured on its front end, the rear end of said plate insertable in said socket, self-acting spring means for clamping said plate in 25 said socket, said spring means consisting of a wire spring the free ends of which engage in notches cut in the sides of said plate, means associated with the socket for preventing movement 30 of the blades in a direction from or toward which a thread is traveling through the device, and means associated with the plate to prevent its improper insertion in the socket.

2. A thread cleaner of the class described comprising, a bracket having means for attaching it to the machine on which it is to be employed and 35 means for attaching one or more thread guides, a support formed on said bracket, a socket pivoted on said support, a plate having a pair of thread-cleaning plates secured on its front end, the rear end of said plate insertable in said socket, self-acting spring means for clamping said plate in 40 said socket, said spring means consisting of a flat spring secured in said socket and having a transverse ridge engaging in a transverse groove formed in said plate, and 45

means associated with the socket for preventing movement of the blades in the direction from or toward which a thread is traveling through the device.

3. A thread cleaner of the class described comprising, a bracket having means for attaching it to the machine on which it is to be employed and 80 means for attaching one or more thread guides, a support formed on said bracket, a socket pivoted on said support, a plate having a pair of spaced thread-cleaning blades secured on its front end, the rear end of said plate insertable in said socket, and self-acting spring means for clamping said plate in said socket, said spring means consisting of a flat spring secured in said socket and 85 having a transverse ridge engaging in a transverse groove formed in said plate.

4. A thread cleaner of the class described comprising, a bracket having means for attaching it to the machine on which it is to be employed and 90 means for attaching one or more thread guides, a support formed on said bracket, a socket secured on said support, a plate having a pair of spaced thread-cleaning blades secured on its front end, the rear end of said plate insertable in said socket, and self-acting spring means for clamping the plate in the socket formed integrally with the socket, said spring means consisting of flat 95 springs having transverse ridges engaging in transverse grooves formed in said plate.

5. A thread cleaner of the class described, comprising, a bracket having means for attaching it to the machine on which it is to be employed and 100 means for attaching one or more thread guides, a support formed on said bracket, a socket swingingly mounted on said support, a plate having a pair of thread-cleaning blades secured on its front end, the rear end of said plate insertable in said socket, the socket made channel-shaped 105 with the edges of the channel bent inwardly towards each other to prevent movement of the thread-cleaning blades in the direction from or towards which the thread is travelling through the device, and self-acting spring means for clamping said plate in said socket.
